JOSEPH HIDY JAMES, OF PITTSBURGH, PENNSYLVANIA, ASSIGNOR TO CLARENCE P. BYRNES, TRUSTEE, OF SEWICKLEY, PENNSYLVANIA

MANUFACTURE OF INTERMEDIATE OXIDATION PRODUCTS AND APPARATUS THEREFOR

Original application filed January 18, 1926, Serial No. 81,963. Divided and this application filed August 10, 1927. Serial No. 212,103.

This invention relates to the manufacture of intermediate oxidation products and is a division of my copending application Serial No. 81,963, filed January 18th, 1926.

5 In said application, Serial No. 81,963, I have disclosed a process and apparatus for the manufacture of intermediate oxidation products from organic bodies, such as hydrocarbons or hydrocarbon derivatives, by the 10 use of a solid oxidant material which will yield oxygen to the organic body under elevated temperature conditions.

In a number of my copending applications, for example, Serial No. 272,567, filed January 22nd, 1919; Serial No. 281,124, filed March 7th, 1919; Serial No. 335,937, filed November 5th, 1919; Serial No. 435,355, filed January 6th, 1921 and Serial No. 520,283, filed December 6th, 1921; I have disclosed

20 processes for making intermediate oxidation products from mineral hydrocarbons such as petroleum or fractions thereof, the products from the low temperature distillation of coals and from shale oil, whether or not said 25 products have been "cracked" prior to oxidation. In these several processes the hydrocarbon in vapor or gaseous phase is mixed with oxygen or an oxygen containing gas such as air, and the mixture is passed 30 through a reaction zone at a temperature between 160° and 500° C. with or without a catalyst. The condensed products of such process are in the range from aliphatic alcohols to hydroxylated aldehyde acids, including alcohols, aldehydes, aldehyde alcohols, esters, ketones, etc.

Such processes, while generally applicable are particularly desirable for liquid hydrocarbons having a boiling range from that 40 of kerosene through the mineral oil fractions of heavier molecular weights. Where fractions lighter than the lower kerosene limit, including gaseous hydrocarbons, are used, the diluting effect of the nitrogen in the air 45 makes it difficult to procure and recover the product. Furthermore, where these lighter hydrocarbons are used, the explosive range, when mixed with air, is quite wide and this increases the working hazard.

50 By using a solid oxidant material as de-

scribed and claimed in my copending application Serial No. 81,963, above referred to, these difficulties are entirely overcome or materially reduced. The hydrocarbons or hydrocarbons or hydrocarbon derivatives are 55 treated with the solid oxidant when such hydrocarbons or hydrocarbon derivatives are in finely divided condition, as for example, a vapor or gaseous phase. The operation is preferably carried out in an atmosphere free, or substantially free, of air, or free oxygen, and at a reactive temperature which will cause oxygen to pass from the oxygen containing material into the hydrocarbon or hydrocarbon derivative. The material, after being thus partially or wholly 60 deoxidized, is withdrawn from the reaction zone and may be regenerated by reoxidation and then reused in the process.

Where, as in the present preferred form of 70 apparatus a movable carrier is provided with an oxidant screen or screens and the carrier actuated either continuously or intermittently, and the hydrocarbon stream is passed through a portion of the screen or screens at 75 a temperature within the reactive range, the used oxidant is preferably reoxidized in other parts of its path, preferably by subjecting it to heated air and keeping it heated in the presence of air, before such portions again 80 pass within the reaction zone.

In the preferred form the operation is cyclic as in one passage only a portion of the hydrocarbon will be partially oxidized. The vapor stream will then pass through a condensing, scrubbing and washing system to extract the partial oxidation products. The remainder of the exit stream will then again pass through a reaction zone and the oxidizing operation be repeated using either the 90 same apparatus or another apparatus of similar type. Fresh hydrocarbon is preferably supplied to the exit stream after extraction of products, and I usually prefer to also tap out a portion of the remaining gaseous stream 95 and supply fresh hydrocarbon sufficient to replace both the tapped out portion and the recovered portion converted into products before repeating the process either in the same or a similar apparatus.

The material which is preferably employed as the oxidant consists of metallic oxides. I have discovered that the class of metallic oxides which I have disclosed as catalysts in the several pending applications above referred to gives the best results. Such oxides are those of the high melting-point, electro-negative, low-atomic-volume metals, particularly those having an atomic weight above 40. 10 These metals appear on the Lothar-Meyer diagram of the periodic series beginning on the descending side of the third peak and extending on the descending side of the fourth peak and the descending side of further peaks later developed. This class includes the following metals: titanium, vanadium, chromium, manganese, zirconium, niobium, molybdenum, tantalum, tungsten and uranium. An excellent oxidant for my present purposes 20 consists of the tri-oxide of molybdenum. I prefer to employ the complex oxides of metals having a varying valence. The parts of the complex may consist of oxides of the same metal or of different metals. Such complexes 25 may be regarded as salts, that is, compounds of one or more basic acid oxides. The basic and acid parts of these complexes may be formed from oxides of different metals, in which case each metal or group of metals used 30 should possess varying valence. The basic oxides may be the lower oxides of the metals in the class named or may be the oxides of iron, copper, nickel, lanthanum, cobalt, thorium or eight or nine rare earth metals. In 35 both acid or basic portions there may, of course, be two or more of these combined. I may use chromic-chromate, tungsten-tungstate, etc. for example.

It will be noted that in my new method 40 and apparatus the hydrocarbon or hydrocarbon derivative is in finely divided form, preferably in the vapor or gaseous phase, while the oxygen is derived from a material containing chemically-combined oxygen and 45 preferably in solid finely divided condition. The temperature will vary according to the hydrocarbon or hydrocarbon mixture being treated. Under the conditions named, the hydrocarbon can be partially oxidized to form 50 intermediate products, such as alcohols, aldehydes and acids. During the process, if a solid oxide is employed, the oxide will pass to a lower state of oxidation, or to the metal itself.

55 My application Serial No. 81,963 describes various forms of apparatus effective for bringing the hydrocarbon or hydrocarbon derivative into the desired intimate contact with the solid oxidant. The present invention 60 specifically covers an embodiment of the broad invention wherein the solid oxidant is supported on an extended carrier or support and the hydrocarbon stream contacts with successive portions thereof. In the preferred 65 form, the oxidant is carried by screens or

pads which are moved in an orbital path so as to bring them into the path of the hydrocarbon or hydrocarbon derivative, and thereafter into a regenerating zone where they are reoxidized.

70 In the accompanying drawings, illustrating the present preferred embodiment of this type of apparatus,

Figure 1 is a side elevation partly broken away or of one form of apparatus which may 75 be used,

Figure 2 is an end elevation of the apparatus shown in Figure 1,

Figure 3 is a vertical transverse section taken on the line III—III of Figure 1.

Figure 4 is a horizontal transverse section taken on the line IV—IV of Figure 1, and

Figure 5 is a vertical transverse section taken on the line V—V of Figure 1.

80 In the illustrated embodiment of the invention, the oxidant is carried by previous screens 50. In a complete cycle of the process the hot vapors or gases to be treated are passed through a pad or screen 50, and are thus oxidized, after which the pad is again supplied with oxygen by subjecting it to heated air. In order to carry out these steps I provide a heating chamber 51 divided into two compartments 52 and 53 by a wheel 54 provided adjacent the rim with a series of 85 openings 50a, into which the screens or pads 50 are secured. The periphery of the wheel fits into a recess 55 which acts as a seal so that substantially the only communication between the portions 52 and 53 of the chamber is 90 through the screens 50. Hot air is supplied to the chamber 52 through a conduit 56 at one side and below and this air passes through the screens 50 and finds an outlet through a stack 57 at the other side of the top. The hot air 95 reoxidizes the oxidant screens for the next treatment of the hydrocarbon vapor, gas or other organic compound being treated.

100 The oxidation of the hydrocarbons is carried out at a treating station indicated generally by the reference character T and the screens are successively carried through this station by rotating the wheel 54. In Figure 1 there is shown a motor 58 connected to the shaft 59 of the wheel through suitable gearing 60 for causing rotation of the wheel at any desired speed.

110 The heated vapor is supplied from a conduit 61 having a downwardly extending portion 62 and a horizontal portion 63 extending into the treating station. The construction is shown in detail in Figures 4 and 5. The conduit 63 terminates in a contact member 64 which terminates in a cheek plate 65 and is 115 slidably mounted in the frame 66.

120 The cheek plate 65 fits into an annular recess 67 in the wheel 51 and it will be noted from Figures 3 and 4 that the openings 50a in which the pads 50 are fitted terminate in the recess. The contact member 64 is pro- 125

vided with an opening 64a adapted to register with one of the openings 50a, while the cheek plates 65 extend vertically so as to cover the adjacent openings 50a and thus prevent any 5 leakage of hydrocarbon vapors from the conduit 63 into the chamber 52 proper. The annulus 67 is provided with packings 68 extending entirely around the wheel, which serve to materially reduce leakage. Leakage 10 is further prevented by the provision of springs 69 carried by studs 70, mounted in the frame 66 and bearing against a collar 71 secured to the contact member 64. By this arrangement the contact member is continually urged against the wheel and a relatively 15 tight sliding joint is secured.

The contact member 64 is duplicated on the other side of the wheel, this being indicated in Figures 4 and 5 at 64'. The contact member 20 64' is provided with a cheek plate 65' which is coextensive with the cheek plate 65, as best shown in Figure 5.

In operation the vapors to be treated enter through the pipe 63, pass through one of the 25 screens 50 and leave the treating station through a conduit 72. The conduit 72 leads into a downwardly extending conduit 73 connected to an outlet 74 through a swivel joint 75.

30 It will be noted that the arrangement of inlet and outlet conduits is such that there is a general downflow of the vapors at all times, so that no condensed hydrocarbons can collect anywhere in the apparatus. As shown in 35 Figure 5 the openings through the contact members 64 and 64' are so arranged that condensed vapors cannot collect therein.

The frame 66 is slidably mounted in a 40 guide 76 built into the furnace wall to permit movement of such frame toward or away from the center of the furnace with expansion or contraction of the wheel. In apparatus of this character the variation in wheel diameter will be a material amount and the arrangement shown prevents jamming of the apparatus. The frame 66 is provided with interior flanges 77 which are packed to prevent 45 leakage. With the movement of the frame 66 inwardly or outwardly, it is of course necessary to move the conduits 63 and 72 correspondingly and the swivel joint 75, together with a similar swivel joint (not shown) on the conduit 61, make this movement possible. Packings 78 are provided on the contact members 64 and 64' for the conduits 63 and 72 so 55 that expansion longitudinally of these conduits may be provided for while maintaining a tight joint and at the same time permit the slight rotation of the conduits which will be occasioned on a movement of the frame 66.

The wheel illustrated in the drawings has been shown as continuously rotated, but it will be understood that a Geneva movement or similar apparatus for providing an intermittent motion on the wheel may be provided

if desired. As shown in Figure 7, the screens 50 are separated from one another only a relatively short distance and when so arranged the continuous rotation is advantageous.

The treating chamber is maintained at 70 suitable temperature by the hot air entering through the opening 56 and the treating station T is so located with respect to the openings 56 and 57 that it will be suitably heated without any undue pressure 75 differential, which would tend to cause leakage, existing at that point. The wheel proper may be made of any suitable material such as cast iron, but it is desirable to make the rim of a close-grained metal which will take 80 a high polish and will not be subject to warping, such as "nickrome," "invar," or "Monel" metal. The contact members 64 and 64' should be made of material which is not subject to warping and preferably has 85 a low coefficient of expansion and contraction.

The temperature in the reaction zone is 90 preferably below 600-700° C. and will vary with the material treated, being often as low as 160-170° C. for example with olefin gases or those containing unsaturated compounds. Methane or fixed gases usually need higher temperatures than vaporized liquids. The temperature for regenerating or revivifying the oxidant is usually higher than that in the reaction zone. A short time of sojourn or contact is preferable to avoid secondary reactions. The process may be used 95 with any kinds of hydrocarbons or hydrocarbon derivatives or compounds, whether aliphatic, aromatic, naphthenic or otherwise. The process may be carried out either at atmospheric, sub-atmospheric, or super-atmospheric pressures. I do not claim herein 100 the metallurgical method of reducing metallic oxides to metals herein disclosed, as that invention is covered in the claims of my co-pending divisional application Ser. No. 550,147, filed July 11, 1931. 105

I have illustrated and described a preferred form of the invention, but it will be understood that it is not limited to such form, as it may be otherwise embodied or practiced within the scope of the following 110 claims.

I claim—

1. In chemical apparatus, a carrier or support arranged to support divided solid oxidant material, an enclosed reactive zone 115 cooperating therewith, connections for passing a chemical in finely divided form in contact with said oxidant material within said enclosed reactive zone, means for causing relative movement between the carrier and said connections and means for revivifying said oxidant material exterior to said reactive zone. 120

2. In chemical apparatus, a movable carrier arranged to support divided solid oxi- 125

dant material, means for moving the carrier, a reactive zone enclosure coacting with a portion of the carrier and connections for passing a chemical in gaseous phase to the reactive zone, and means for supplying heat to and revivifying the oxidant exterior to the enclosure.

3. In chemical apparatus, an endless carrier arranged to support divided solid oxidant material, means for moving the carrier in a continuous manner, a reactive zone enclosure coacting with a portion of the carrier and connections for passing a chemical in gaseous phase to the reactive zone, and means for supplying heat to and revivifying the oxidant exterior to the enclosure.

4. In the method of making organic compounds, the steps consisting of feeding a stream of an organic compound through an enclosed reactive zone, bringing it in said zone into contact with a supported layer of a solid chemical compound capable of releasing a reactive gas, maintaining conditions in the zone to cause release of said reactive gas from the layer, causing relative movement to expose successive portions of the solid chemical compound to the stream, and revivifying successive portions of the solid compound while retained in the support.

5. In chemical apparatus, an enclosed reactive zone, means for applying heat thereto, a support extending through the zone and arranged to receive a layer of a solid chemical compound capable of releasing a reactive gas under the zone conditions, connections arranged to feed a chemical in finely divided form through the enclosed reactive zone, and means for causing relative movement between the support and zone to bring fresh portions of the solid chemical compound into contact with that finely divided chemical passing through the zone.

In testimony whereof I have hereunto set
45 my hand.

JOSEPH HIDY JAMES.
